UNITED STATES PATENT OFFICE.

WILLIAM JOHN BARBER, OF CLEVELAND, OHIO.

GAS-BURNER.

1,267,355.

Specification of Letters Patent. Patented May 28, 1918.

Application filed September 12, 1917. Serial No. 190,882.

To all whom it may concern:

Be it known that I, WILLIAM JOHN BARBER, a citizen of the United States, residing at Cleveland, in the county of Cuyahoga and State of Ohio, have invented certain new and useful Improvements in Gas-Burners, of which the following is a specification.

This invention pertains to improvements in gas burners for heating furnaces, and the invention consists in a burner constructed and adapted to operate substantially as shown and described and particularly pointed out in the claims.

In the accompanying drawings Figure 1 is a side sectional elevation of a furnace on line 1—1, Fig. 2, with my new style of burner installed therein; Fig. 2 is a front elevation of the furnace and the burner therein, with the ash pit door removed and the furnace broken away at the top.

Fig. 3, Sheet 2, is a plan view on line 3—3, Fig. 2, above the grate-bars and burner. Fig. 4 is an enlarged partially sectioned elevation of a portion of the burner, and Fig. 5 is a cross section on line 5—5, Fig. 4, showing the inclination of the jet orifices for the gas and the top of pilot lighting tube, which is central between the burner units.

Simplicity, cheapness and efficiency are the key words to the present invention.

For example, all other burners with which I am familiar and employed for domestic or other heating furnaces, ranges and the like, are universally provided with some sort of air mixer, but the present burner does not contain a mixer of any sort and depends exclusively on the original discovery that more perfect combustion and a better heating effect can be obtained by means of burner tubes which have opposite gas jets adapted to discharge the gas inward toward each other from opposite sides and in which the jets are so arranged that the gas streams therefrom meet at the natural point of combustion in the open air, say at about the angle indicated by the arrows in Fig. 5. That is, the gas issuing from said jets under what may be regarded as normal pressure will commingle with air at the natural combustion distance from the pipes and burn at the meeting angle described, or at about that point.

This juncture of the gas streams from the opposite side jets naturally sets up a mixture with the air peculiar to itself by the fact of confluence, and I have found that such mix-

ture or admixture not only produces what may be termed perfect combustion but consequent economy in the volume of gas consumed and total absence of carbon deposits in the furnace. Furthermore, I can obtain combustion and the best of heating effects from a lower pressure of gas than from any other burner that has come under my observation.

Now, referring specifically to the construction of the burner, 2 represents the gas supply pipe with which each individual burner unit 3 is connected by a pipe 4 of its own and which comprises a vertical pipe joint or section 5. The said burner units each consist in this instance of a tube or pipe bent to approximately U-shape, and there are four such units as shown and disposed at right angles to each other in the furnace, substantially as seen in plan, Fig. 3. The said burner units also are shown as positioned above or over the grate bars 6 and the vertical pipe sections 5 extend between the said bars and above the same as shown. The sides of the said burner units between their ends are parallel and spaced apart at a predetermined distance so that the gas stream issuing from the opposite inwardly inclined jets or orifices 7 will flow to a common meeting point and burn midway between said sides and above the same as indicated in Fig. 5, or approximately as therein suggested by the arrows, and subject somewhat to the gas pressures. A plurality of gas jets 8 in sets oppositely are provided in each burner unit, say three or more in each, for furnaces of average size.

Each burner unit has its own valve *v* and valve control, and I preferably employ a controlling mechanism adapted to operate the valves from the living apartments or rooms in upper floors, a dial 7, which has figures 1, 2, 3 and 4 on its face, tells the number of units in service. If the indicator 10 or finger 13 points to any given figure it tells that that number of units are open, and to control the same I provide each valve with a toothed sector or segment 8 which is adapted to be turned independently and also to be placed in working engagement with a horizontal slidable sprocket chain 9, or its equivalent, having a suitable support and which has a cable 10 attached to its end and stretched over sheaves 12 and operatively engaged with the rotatable finger or indicator 13 for the said dial. One or more of the said

segments may be operatively engaged with the said chain or rack-bar to open and close the valve or valves at will.

An upright pilot lighting burner 15 is shown centrally in respect to the several burners 3 and provided with jet openings for gas from which to light the burner units. The said pilot may be permitted to burn at all times through the season when heat is required, so as to make the starting of the furnace available from the living room and avoid going to the basement for this purpose. A feed pipe 16 for the pilot light connects with the supply connections 2 and has a valve of its own as usual with such devices.

Combustion being complete there are no deleterious products of combustion emitted, and I have erected and used this burner for hours in a closed room without discovering any odors whatever coming therefrom.

The invention is shown in connection with a heating furnace, but it can be more or less variously used in grates, floor heaters and the like and is not therefore to be regarded as limited to heating furnaces in its adaptation or use, and the arrangement of the burner units may be changed without departing from the invention.

In operation the matter of normal or maximum gas pressure should be considered, and the jet orifices are made larger or smaller accordingly. For example, when the pressure is several ounces the orifices should be about a thirty-second of an inch, and higher pressures will require correspondingly larger orifices or holes. But once having the orifices suited to the normal or maximum pressure, as in the case of natural gas, where pressures run down in excessively cold weather, the burner is self accommodating to the lower pressures and

requires no regulation by any means whatever. In fact, all regulation by the valves is bad because it contributes to imperfect combustion. Hence the proper method is to get the orifices of the right size to begin with and then open wide the valves and let the burner regulate itself, which it will. The valves therefore are really only for shut-off purposes, and the temperature in the room is governed by using one or more heating units according to the amount of heat wanted. For this reason also the units are made separate and several are employed so as to get the maximum and the minimum heating effects at will.

What I claim is:

1. A gas burner unit consisting of a relatively small pipe bent back upon itself near its middle with a U bend and the sides thereof provided with opposite gas jets inclined inwardly and upwardly at an angle of approximately forty-five degrees to a vertical plane and one end of said unit open to make pipe connection therewith. 60

2. A gas burner unit consisting of a single piece of pipe bent substantially U-shape and having parallel sides provided with oppositely disposed gas jets in their inner sides said jets spaced apart to approximately one-fourth the length of the unit. 65

3. A hot air furnace and a plurality of substantially U-shaped burner units disposed about a common center therein having opposite inwardly inclined gas jets along the inner and upper side portions of the sides of each unit and a pilot lighting burner located in said center to ignite said units.

Signed at Cleveland, Ohio, this 8th day of September, 1917.

WILLIAM JOHN BARBER.
